J. K. GILLAM

BRICKKILN

Filed Jan. 27, 1926

UNITED STATES PATENT OFFICE.

JOHN K. GILLAM, OF KITTANNING, PENNSYLVANIA.

BRICKKILN.

Application filed January 27, 1926. Serial No. 84,137.

This invention relates to improvements in brick kilns, the specific invention being directed more specifically to the firing system of brick kilns.

5 The primary object of the invention is an improved firing system for brick kilns.

Another object of the invention is the provision of a centrally located underground firing and heating system for brick kilns.

10 Another and further object of the invention is the provision of a firing system for brick kilns which will greatly lessen the present fuel cost for heating kilns and will additionally effect a saving of time in the

15 burning of bricks and additionally effect a saving as to loss caused by the over-burning of bricks.

A still further object of the invention is the provision of a firing system for brick 20 kilns in which the kiln walls proper are practically the same as in the ordinary kiln but will eliminate openings in the kiln walls and also eliminate the necessity of "bagwalls" and thereby obviate the necessity and expense 25 of building said "bagwalls" as has heretofore been the case.

A further object of the invention is the provision of a firing system by reason of which greater room is given in the kiln 30 chamber proper for the reception of bricks to be burned.

A still further object of the invention is the provision of a firing system for brick kilns by reason of which the finished burned 35 bricks will be of a better grade and quality than those produced in the common form of brick kiln now known and used.

Other further objects and novel features 40 of construction and improved results of the invention will appear from the following description and accompanying drawing.

In the drawing:

Figure 1 is a vertical sectional view 45 through a kiln having incorporated therewith the improved firing system;

Figure 2 is a transverse section taken on the line 2—2 of Figure 1, looking in the direction indicated by arrows;

Figure 3 is a fragmentary transverse sectional view taken on the line 3—3 of Figure 50 1, looking in the direction indicated by arrows.

To those skilled in the art, it is well known that the cost of the fuel consumed in burn-

ing a kiln of brick is the most important 55 item as to making the finished product expensive. Practically all kilns in this country are fired from fire boxes just inside the outer wall or rim of the kiln.

In kilns of this construction when used 60 for burning gray brick, it has been found necessary to rebuild the "bag-walls" twice a year. It is of course, also necessary to have openings in the kiln wall, because of the fire box. It has also been found that in kilns 65 of this nature there has been great difficulty encountered in burning those bricks in the center of the kiln to a sufficient hardness.

Ordinarily in a brick kiln having an inside measurement of 28 feet, there are eight 70 fire holes or fire boxes with either a circular or square wall of brick, 8 inches thick around each fire hole or box. This wall is for the fire or gas to burn against and is what is commonly known as the "bag-wall". 75 There is approximately 10 square feet in each of these walls and it will therefore be seen that these walls take up a considerable amount of the room or space in the interior of the kiln heating or burning chamber. 80

Knowing the above enumerated disadvantages of the ordinary brick kiln construction, I have invented and devised an improved firing system for brick kilns which will overcome these deficiencies and results 85 in the production of better bricks.

As will be hereinafter seen this invention will eliminate the expense of building "bag-walls", prolong the life of the kiln outer wall by taking the fires away from this wall 90 and by reason of the manner of firing, reduce to a very small amount the number of bricks which are subjected to severe heat which causes them to be over-burned or flashed so that they must be sold at a reduced price 95 as a common grade brick.

Referring to the several figures of the drawing in which like parts are designated by similar reference numerals, it will be seen that the kiln proper is circular in form, comprising an outer wall 5 surmounted by a dome 6 and having a floor 7 whereby the kiln heating or burning chamber 8 is provided.

Extending transverse the kiln, below the floor, there is a tunnel 9 which is divided intermediate its length and centrally of the kiln by a flash wall 10. The tunnel adjacent the flash wall 10 is somewhat enlarged and

is provided with a series of burner holes 11 which are formed by reason of the separated vertical walls 12. These fire holes are adapted to receive the gas or oil burners 13, the common feed line 14 of which extends outwardly through the tunnels to a suitable source of supply. Access to the tunnel is had by means of the steps 15. By reason of the construction described there is 10 provided the fire or burner chambers 16 on either side of the flash wall intermediate the wall and the fire or burner openings.

The burner chambers 16 are in communication at their upper ends as at 17 with the 15 interior of the kiln heating chamber 8.

The floor 7 is provided with circular flues 18 and 19. The flue 18 is adjacent the central burner chamber outlet 17 while the flue 19 is positioned just within the wall 5 of the 20 kiln. These circular flues are in communication with the radially extending horizontally arranged flues 20 which are in turn in communication with the outlet stacks or chimneys 21 built in the kiln wall.

25 Attention at this time is directed to the fact that the circular flues 18 and 19 could be changed without departing from the spirit of the invention and might readily be replaced by a series of small squares or 30 rectangular openings having communication with the outlet chimneys. If desired, all of the radial flues could be led to a single chimney rather than to several as shown in the drawings.

35 It is intended that green brick be piled or arranged in a circle as shown at 22 around the outlet openings 17 so that the heat from the burner chamber will be carried upwardly within a few feet of the crown or dome 6 of the kiln and from this point will be 40 drawn downwardly through the piles or rows of bricks and pass outwardly through the flues 18, 19, and 20 and chimneys 21.

It will be understood that the kiln chamber 8 will be piled circularly with brick to a point adjacent the ring or outer wall 5 as designated by the numeral 23. These circular piles of bricks, however, will start at a point outside of the circular flue 18 and 50 stop short of the circular flue 19 and will be piled loosely whereas the brick in the circular green brick flue 22 will be piled tightly and closed to prevent the escape of the heat until the upper end of the flue adjacent the 55 kiln dome, is reached. By this arrangement there is in reality formed flue-ways 24 and 25 in communication with the circular flues 18 and 19 respectively.

With bricks arranged in the above manner 60 the heat will pass in among the bricks which are loosely piled or set with the result that the bricks will burn uniformly in all parts of the kiln.

It will be readily evident that the person 65 operating the kiln can enter the tunnel 9

and light the burner 13 and that means can be there at hand for the proper adjustment of the burners. These burners will burn against the flash wall 10 and the heat will then pass upwardly through the opening 17, 70 temporary flue 22 and thence downwardly through the bricks and outwardly through the chimneys 21. The air intake for the kiln is had through the tunnel 9 and the chambers 16 are sufficiently large to provide 75 the necessary air for combustion. By reason of this firing system, the flash wall 10 can be readily and easily repaired whenever necessary.

From the foregoing it will be seen that I 80 have provided a firing system for brick kilns which overcomes the objectionable features common in the form of brick kilns now in use.

Although the present invention is described as being particularly adapted for the firing and burning of brick it will be readily understood that practically any product made of clay can be readily fired or burned in a kiln constructed in accordance 90 with my invention.

What I claim is:

1. A brick kiln or the like, comprising a kiln chamber adapted to receive the brick to be burned, a tunnel beneath said chamber and extending transverse the same, a flash-wall in said tunnel and burners for directing fire against said flash-wall, passage-ways for the heat from said burners to pass into the kiln chamber, the brick in said kiln chamber piled to form a flue for directing said heat to the upper part of the kiln chamber, flues in said kiln chamber floor in communication with chimneys for carrying off said heat after the same has circulated through the brick, and said tunnel providing inlet means for cold air to the burners and a walk-way, whereby the burners can be reached by an operator for regulation.

2. A system for heating the burning chamber of a kiln or the like, comprising a tunnel beneath said kiln having therein a flash-wall against which the heating medium is directed, communication between the tunnel and the kiln for the passage of the heat upwardly thereinto, and said tunnel acting as a cold air-inlet for the burners and as a walk-way whereby the burners can be reached for regulation and the flash-wall for repair.

3. A system for heating the burning chamber of a kiln or the like, comprising a fire-chamber located centrally beneath said kiln, communication between said fire-chamber and kiln for the passage upwardly of heat, flues in the floor of said kiln for carrying the heat to outlet chambers, and the brick being burned in the kiln piled to form an up-draught from the fire-chamber inlet and a down-draught to the floor outlet flues,

whereby there is provided a combined up and down draught kiln with an underground central heating chamber.

4. A kiln or the like adapted to be heated by gas or fluid burners, comprising a kiln chamber having central communication with a tunnel extending transverse and below

said chamber, a flash-wall in said tunnel against which said heating burners direct their heat, and said tunnel acting as a walk-way and a cold air inlet. 10

In testimony whereof I hereunto affix my signature.

JOHN K. GILLAM.
